Top 8 Best Full Face Snorkel Masks 2017, posted at vbestseller.com, earliest date reviewed on May 20, 2017, [online], acquired on Apr. 10, 2018. Available from Internet, <URL: <https://vbestseller.com/best-full-face-snorkel-mask-reviews/>> (Year: 2017).*

Primary Examiner — Lilyana Bekic

Assistant Examiner — Aula Soroush

CLAIM

The ornamental design for a snorkeling mask, as shown and described.

DESCRIPTION

FIG. 1 is a front elevational view of a snorkeling mask showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top perspective view thereof;

FIG. 8 is a bottom perspective view thereof;

FIG. 9 is an enlarged view of portion 9 shown in FIG. 1;

FIG. 10 is an enlarged view of portion 10 shown in FIG. 2;

FIG. 11 is an enlarged view of portion 11 shown in FIG. 3;

FIG. 12 is an enlarged view of portion 12 shown in FIG. 4;

FIG. 13 is an enlarged view of portion 13 shown in FIG. 6;

and,

FIG. 14 is an enlarged view of portion 14 shown in FIG. 8.

The broken lines depict portions of the snorkel mask that form no part of the claimed design.
